BOTTLE

Abraham Y. Schultz, University City, Mo.

Application January 7, 1953, Serial No. 23,044

Term of patent 14 years

(Cl. D58—6)

To all whom it may concern:

Be it known that I, Abraham Y. Schultz, a citizen of the United States, residing at University City, county of St. Louis, State of Missouri, have invented a new, original, and ornamental Design for a Bottle, of which the following is a specification, reference being had to the accompanying drawings, forming a part hereof—

Fig. 1 is a top view of a bottle embodying my design;

Fig. 2 is a front elevational view thereof; and
Fig. 3 is a side elevational view thereof.

The rear and side views not shown are the same as the views shown.

I claim:

The ornamental design for a bottle, as shown and described.

ABRAHAM Y. SCHULTZ.
